(57) **CLAIM**

The ornamental design for a portable flow hood, as shown and described.

DESCRIPTION

This application is related to U.S. Utility patent application Ser. No. 63/425,238, filed Nov. 14, 2022, entitled "Flow Hood", which is hereby incorporated by reference in its entirety for all purposes.

FIG. 1 is a front, right perspective view of an embodiment of a portable flow hood in accordance with the present design in a first configuration;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a front, right perspective view of the portable flow hood of FIG. 1 in a second configuration; and,

FIG. 9 is a front elevation view of the portable flow hood of FIG. 1 in the second configuration.

Portions of the portable flow hood shown in evenly spaced broken lines depict environmental structures that form no part of the claim.

1 Claim, 9 Drawing Sheets
